[57] **CLAIM**

The ornamental design for a mobile home perimeter foundation, as shown and described.

DESCRIPTION

FIG. 1 is a top, front and left side perspective view of a mobile home perimeter foundation showing my new design;

FIG. 2 is a top plan view thereof;

FIG. 3 is a front elevational view thereof and a mirror image of the rear elevational view thereof;

FIG. 4 is a left side view thereof and a mirror image of the right side view;

FIG. 5 is a bottom view thereof; and,

FIG. 6 is a cross-section thereof along the line 6—6 of FIG. 2.
